(57) **CLAIM**

We claim the ornamental design for a refrigerated display
case, as shown and described.

DESCRIPTION

FIG. 1 is a perspective view of a refrigerated display case
embodying the present invention.

FIG. 2 is a front view of the refrigerated display case shown
in FIG. 1.

FIG. 3 is a side view of the refrigerated display case shown
in FIG. 1; and,

FIG. 4 is an opposite side view of the refrigerated display
case shown in FIG. 1.
